Primary Examiner — Mojtaba Tehrani

(74) *Attorney, Agent, or Firm* — Woodard, Emhardt, Henry, Reeves & Wagner, LLP

CLAIM

The ornamental design for combined serrations for a firearm slide as shown and described.

DESCRIPTION

FIG. 1 is a right, front, perspective view of the combined serrations for a firearm slide showing our new design;

FIG. 2 is a right, rear, perspective view thereof;

FIG. 3 is a right side view thereof;

FIG. 4 is a left side view thereof;

FIG. 5 is a top view thereof;

FIG. 6 is a bottom view thereof;

FIG. 7 is a front view thereof; and,

FIG. 8 is a rear view thereof.

The broken lines illustrate portions that form no part of the claim. The interrupted lines illustrate portions where length forms no part of the claim.

1 Claim, 6 Drawing Sheets
